UNITED STATES PATENT OFFICE.

EDWARD J. BOLAND, OF FREEPORT, ILLINOIS, ASSIGNOR OF ONE-THIRD TO MATTHIAS L. CONLEY, OF FREEPORT, ILLINOIS.

RAIL ANTICREEPING AND TIE-PLATE DEVICE.

Application filed April 19, 1926. Serial No. 103,140.

This invention relates to improvements in rail anti-creeping and tie plate devices, having for an object to provide a device of this character, which when engaged with a rail, will function to absolutely prevent the so-called "creeping" of the rail in either longitudinal direction irrespective of the character, weight or other peculiarities or conditions of railway rolling stock passing thereover and frequently causing such undesirable and highly dangerous action.

It is likewise an object of the invention to provide a rail anti-creeping device adapted to be springingly and bindingly engaged with the adjacent portion of a rail base, and with an appropriate portion of the tie plate employed in connection therewith, whereby the engaged rail will be firmly anchored to the tie plate and tie against longitudinal shifting or "creeping" movement in either direction by reason of rolling stock stresses applied thereto.

Another and equally important object of the invention may be stated to reside in the provision of a device of the character mentioned which is of simple construction and mode of application or installation, it being practicable to apply the device to a rail at all seasons of the year without regard to extreme weather conditions, during either summer or winter, since such application does not require the digging of ballast or other similar preparation required with installation of the now prevalent types of rail anchors.

Yet another object of the invention may be stated to reside in the provision of an anti-creeping device which will, with installation, effect a material saving in track laying and maintenance expenses, in that the device is effective in the prevention of rail creeping in either direction and consequently upon this, some one-half of the number of the now prevalent types of rail anchors, which function to prevent rail creeping in one direction only, will be required.

Other objects of the invention will be in part obvious and in part pointed out as this description proceeds into and on through the specification.

In order that the invention and its mode of operation may be understood by those skilled in the art, I have in the accompanying illustrative drawings and in the detailed

following description based thereupon, set 55 out several embodiments of my invention.

In these drawings:

Figure 1 is a fragmentary perspective view of a rail having my improved anti-creeping device and tie-plate engaged therewith, 60

Figure 2 is a vertical transverse section through the same,

Figure 3 is a vertical longitudinal section, in fragment, taken on the line 3—3 of Figure 2,

Figure 4 is a plan view of the improved tie-plate,

Figure 5 is a vertical transverse section through a slightly modified form of tie-plate,

Figure 6 is a fragmentary vertical longitudinal section taken on the line 6—6 of the Figure 5,

Figure 7, is a slightly enlarged side elevation of my improved rail anchor when applied to a rail, a portion of the latter being shown in section, and which may be used without the aid of the tie plate.

Having more particular reference to the drawings, in connection with which like 80 characters of reference will designate corresponding parts throughout, the improved device may be stated to comprehend a tie-plate, preferably formed of a sheet or block of metal substantially rectangular in configuration as is indicated by the numeral 1, the upper face of this tie-plate proper being formed with a series of longitudinally aligned and similarly disposed rail base shoulders or lips 2, while spike receiving 90 openings 3 are provided at intervals throughout the area of the tie-plate and preferably at portions adjacent the opposite side or marginal portion of the rail base R, as is shown in the Figures 1 and 2, whereby the tie-plate may be firmly secured and anchored to a tie and likewise, to effect, at the same time, a tying connection as between the rail R and said tie-plate 1. This tie-plate 1 is also provided, in the intermediate portion of its upper face with a slot or pocket 4, arranged in a direction transversely of the base of the rail R as is illustrated in the Figure 2, the purpose of which will be subsequently described.

The anti-creeping device proper or rail anchor may be stated to comprise a single piece of spring metal bent intermediately of

itself to provide upper and lower portions 5 jaws 5 and 6 respectively, the lower portion 6 being of a greater length than the upper portion 5 while the intermediate or bent portion of the anchor is curved upon itself into a semi-circular formation as designated by the numeral 7, said upper jaw 5 being offset from the adjacent portion of said semi-circularly formed bend 7 and having its lower marginal portion formed so as to intimately contact, throughout its length, with the adjacent portion of the upper face of the rail base, aforesaid.

The rail anchor is adapted to be received longitudinally of the slot or pocket 4 formed in the tie plate 1 after the fashion shown in the Figures 1 and 2 and as will be noted, the curved outer end or semicircular formation 7 thereof lies adjacent to the outer end shoulder of said slot or pocket and in having bearing thereupon, it will be appreciated that said shoulder will act as an effectual means for preventing undue displacement or corresponding movement of the rail anchor with respect to the tie plate 1. This means of securing the rail anchor against displacement or similar movement is furthermore accentuated by the fact that the rail anchor is of a width or thickness which will cause the same to extend below the lower face of the tie plate 1 and into the tie T, some distance, thus producing a tendency to secure the rail anchor in place and to prevent it from becoming loose. Thus, the necessity of additional means for fastening the rail anchor to the tie plate is eliminated and furthermore, it is not necessary that the anchor be extended the full width of the tie plate, as is the case with various forms of anchoring devices now prevalent in this art. Furthermore, it will be appreciated that since the rail anchor proper is formed of spring metal, the same will springingly and bindingly engage upon an adjacent portion of a rail base and such engagement will serve to positively prevent the anchor from becoming loose, when once applied or engaged with a rail base.

It is preferable that the inner free end of the lower portion of the rail anchor, that is, that portion designated by the numeral 6, be formed with a beveled or similarly formed portion designated by the numeral 8 so that when said end of the rail anchor is forced into the slot or pocket 4, the same will be permitted to pass freely in its transversal path of movement over the lower side of the rail base, that is, this beveled end 8 will serve to guide the rail anchor as it is being driven into place with respect to the tie plate and the rail base; serving much after the fashion of an ordinary skid surface.

The lower face of the jaw 6 of the rail anchor is formed with a substantially straight rail base engaging portion, as shown

in the Figure 2; the inner end of said lower jaw being thicker than the outer end thereof, as shown in the Figure 7; that is, that end of the same adjacent the semi circularly formed bend 7. The upper face of this lower jaw 6 of the anchor inclines from the enlarged free end thereof towards its outer end which terminates in the bend 7, whereby this jaw 6 is of a wedge shaped formation. The jaws 5 and 6 being resiliently connected by means of the bend 7 will when the rail base is placed therebetween grip the same so as to prevent the anchor from becoming loose. The anchor being seated within the tie plate the latter will also assist in preventing the displacement of the anchor. However, when the anchor is applied to the rail base without being embedded within a tie plate as shown in Figure 7, the weight of the rail and rolling stock passing thereon will cause the lower jaw 6 to bite into or be embedded into the tie and as the anchor is in gripping engagement with the rail the creeping of the latter in a longitudinal direction will be prevented. The jaws 5 and 6 are substantially square in cross section providing relative sharp edges which may bite into the upper and lower surfaces of the rail base or the upper face of the rail tie should the anchor be tipped or inclined caused by the creeping movement of the rail in a longitudinal direction.

Because of the manner and mode of engagement of the anchor with the rail base and the fact that the lower face of the jaw 6 has a direct engagement with the adjacent portion of the rail tie, it will be understood that any attempt at longitudinal shifting or creeping movement of the rail will serve to effect a fulcrumming of the anchor, hence moving the same to a canted position as is illustrated in Figure 3 whereby one edge of each jaw 5 and 6 will bite into the rail base and another edge of the jaw 6 will bite into the tie thereby increasing the grip between the tie and rail therefor. Obviously when the anchor is rocked or moved to a canted position the rail base will cause the jaws 5 and 6 to be further forced apart, but as they are resiliently connected, their firm grip upon the rail base will not be decreased.

In the Figures 5 and 6, I have shown a slightly modified form of tie-plate for use in connection with the improved anti-creeping device or rail anchor. Herein, said tie-plate, designated for convenience by the numeral 1', instead of being formed with a slot as designated by the numeral 4 in the preceding embodiment, such tie-plate is formed only with a recess designated by the numeral 4', such recess being arranged in a fashion corresponding to that of the recess of the slot 4, but obviously, not passing completely through the tie-plate. Also,

one end of this recess is preferably curved as indicated by the numeral 9, while the opposite end thereof is beveled as at 10 to correspond with the beveled free end of 5 the longer lower side 6' of the rail anchor. When the anchor is moved to a canted position as illustrated in Figure 6 the lower jaw 6' of the anchor will have a biting engagement with the tie plate 1'. The anchor as shown herein is seated within the tie-plate and does not rest upon the tie as shown in the preferred embodiments of the invention. When the rolling stock passes over the rail in one direction the anchor will be 10 rocked to the position as shown in Fig. 3 and when the rolling stock travels in an opposite direction the anchor will be canted to the position as shown in Fig. 6.

In the installation of my improved anti-creeping device, it is to be understood that the rail anchor hereinbefore referred to is engaged in the pocket 4 or 4' of the tie-plate before the tie-plate is applied to the rail. After the rail anchor is engaged in the 20 plate in the fashion shown in the Figures 2 and 5, the tie-plate together with the anchor is introduced endwise under the rail and up to such a point as to where the anchor becomes engaged with the adjacent portion of 25 the base of the rail. Following this engagement, a heavy maul or similar implement is employed to effect a driving engagement of the anchor in its embraced engagement with the adjacent side or portion of the base of 30 the rail R and by the time the rail anchor has been properly engaged in its permanent position with the adjacent portion of the rail base, the tie-plate has likewise reached its proper position beneath the rail and adjacent the receiving tie T. In other words, 35 the rail anchor and the tie plate are positioned simultaneously with respect to the rail and the tie and following this, the tie plate is then firmly anchored or secured in position upon the tie T by driving spikes or similar fastening devices through the various openings 3 into the adjacent portions of the tie. With engagement of the rail anchor with the base of the rail R in the manner 40 hereinbefore described, the same will function to absolutely prevent the objectionable longitudinal shifting or "creeping" of an equipped rail, in that the springing and binding engagement of the anchor upon the 45 base, accentuated by the canting positioning of said anchor with respect to the adjacent portion of the rail, will afford a positive connection as between said rail R and the tie T. Similarly, because of the mode of engagement 50 of this anchor with the rail base and the engagement of the lower side 6 or 6' in the pocket 4 or 4' of the tie-plate 1, it will be appreciated that such anchor will effectively function to prevent longitudinal shifting or "creeping" movement of the equipped 55

70 rail in either direction, irrespective of the character or nature of the stresses applied thereto during the passage of rolling stock over the equipped rail R.

Manifestly, the construction shown is capable of considerable modification, and such modification as is within the scope of my claims, I consider within the spirit of my invention.

75 I claim:—

1. A device of the character described, comprising in combination with a tie-plate having a transversely disposed opening therein, an anchor consisting of a single piece of spring metal bent upon itself intermediately of its ends whereby to effect snug embracing engagement with portions of the opposite sides of a rail base, the upper side of said piece having an offset portion formed with a straight surface intimately 80 contacting throughout its length with the adjacent face of the rail base and the lower side of said piece being formed with a straight inner face adapted to engage with the lower face of said rail base and transversely extend thereover to a point beyond the middle thereof, said lower side of the piece being snugly received in said transversely disposed opening in the tie-plate. 85

90 2. A device of the character described, comprising in combination with a tie-plate having a transversely disposed opening therein, an anchor consisting of a single piece of spring metal bent upon itself intermediately of its ends whereby to effect snug 95 embracing engagement with portions of the opposite sides of a rail base, the intermediately bent portion of said piece being of a semi-circular formation and the upper portion of said piece having an offset part 100 formed with a straight inner face and adapted to intimately contact throughout its length with the adjacent face of the rail base, and the lower side of said piece being formed to engage with the lower face of 105 said rail base and transversely extend thereover to a point beyond the middle of the same, said lower side of the piece being slidably received in said transversely disposed opening formed in the tie-plate. 110

115 3. In a combined anti-creeping and tie-plate device, said tie-plate comprising a flat piece of metal having a series of upstanding lips formed on its upper surface and a plurality of spike receiving openings therein, certain of which are in proximity to said lips, the intermediate portion of said plate having a slot formed therein and so disposed as to be arranged transversely of the base of a rail arranged thereon, one end of said slot 120 being extended for a distance beyond the adjacent marginal portion of said rail base, and said anchor comprising a single piece of spring metal bent intermediately upon itself whereby to effect snug embracing en- 125

120

125

130

gagement with portions of the opposite sides of a rail base, said intermediately bent portion of the anchor being of semi-circular formation, the upper side of the anchor having an offset portion intimately contacting throughout its length with the adjacent face of the rail base and the lower side of said anchor being formed with a straight inner face engageable with the lower face of said rail base and transversely extended thereover to a point beyond the middle of the same, said lower side of the anchor being slidably introduced into and received in said slot formed in the tie-plate.

4. A device of the character described, comprising in combination with a tie-plate, an anchor consisting of a piece of spring metal bent upon itself whereby to effect snug embracing engagement with portions of the opposite faces of a rail base, the upper side of said piece having an offset portion intimately contacting throughout its length with the adjacent face of the rail base and the lower side of said piece having its inner extremity thicker than the outer portion thereof whereby to effect binding engagement of the anchor when engaged with a rail, said lower side of the anchor being snugly received in a transversely disposed opening in the tie-plate.

5. A device of the character described, comprising in combination with a tie-plate, an anchor comprising a piece bent intermediately upon itself whereby to embracingly engage with the opposite faces of one side portion of a rail base, said tie-plate having an opening formed transversely of a portion thereof, the lower side of said anchor being snugly received in said slot and having its outer end in abutting engagement with the adjacent end of the slot, and the free portion of the lower side of the anchor being thicker than the outer portion thereof

whereby with positioning of a rail thereupon and the passing of rolling stock over the rail said anchor will be caused to exert a binding action on the rail to prevent creeping thereof.

6. A rail anti-creeping device comprising a rail base embracing clip seated upon the rail tie adapted to be moved to a canted position by the passing of rolling stock over the rail whereby to effect a biting engagement of the same with a portion of the rail base and the rail tie seating the same.

7. A rail anchor comprising a clip formed from a metal bar bent upon itself to provide an upper and a lower jaw and a curved portion connecting said jaws, said jaws being substantially square in cross section, the free end of the lower jaw being enlarged, the upper face of said lower jaw being inclined towards the curved portion of the clip and adapted to engage the lower surface of a rail base, said upper jaw being adapted to engage the upper surface of the rail base, said upper and lower jaws being adapted to have a gripping engagement with the rail base when said clip is rocked to a canted position and the enlarged free end of said lower jaw being adapted to effect a biting engagement with a rail tie.

8. A rail anti-creeping device comprising a rail base embracing member adapted to be rocked to a canted position by the passing of rolling stock over the rail, said rail base embracing member comprising a pair of jaws extending about the base of the rail, both of said jaws being caused to engage the rail base when said member is rocked to a canted position and one of said jaws having a biting engagement with the rail tie seating the same.

In witness whereof I have hereunto set my hand.

EDWARD J. BOLAND.
